EDWIN L. CONNOR, OF PROVIDENCE, RHODE ISLAND.

SAFETY RAZOR.

Application filed August 2, 1927. Serial No. 210,117.

This invention relates to safety razors and is more particularly concerned with the provision of a razor structurally economical for manufacture and functionally advantageous for use.

An object of the invention is to provide a razor comprising a blade holder structurally simple and capable of manufacture by the metal stamping operations so largely used today, which holder embodies certain novel and advantageous features hereinafter pointed out and effective to improve the shaving operation.

As used today, the highest cutting efficiency of the razor blade is prevented by the accumulation thereon of lather and hair. The lather has performed its task before the blade reaches it and it is not necessary to the edge of the blade in its hair severing action. While from the standpoint of every-day and every-way use of safety razors, it is impossible, practically, entirely to prevent the accumulation of lather upon the razor edge, the construction provided for by the present invention among its features embodies means normally tending to prevent such accumulation and effective largely to reduce it. This construction also has an objective, the support of a blade with its edges free and unhampered by holder structure.

The blade holder of the structure involved herein is intended for use in connection with the well known type of single edged razor blade having its non-cutting rear edge embraced by a U-shaped holder clip, and embodies as a further feature of the invention an advantageous form of blade positioning means, and additionally, clamping means for retaining the blade in proper position. In positioning the blade, I have taken advantage of the standard size of blade and clip with the edge of the clip a standard distance from the cutting edge of the blade and have used a positioning bar which cooperates with the clip edge and leaves the razor edge free and unobstructed. In maintaining a blade so positioned on the holder, the retaining means used is held against displacement by the handle of the holder which is detachable and makes for compactness in the razor. The act of assembling or dis-assembling the razor of the present invention, therefore, results in the clamping or releasing of the blade retaining means.

These and other features will be more clearly

apparent from the following detailed description, read in conjunction with the accompanying drawings forming part thereof and in which:

Fig. 1 is a perspective view of one form of 60 razor embodying my invention,

Fig. 2 is a top plan view of the back of the blade holder thereof.

Fig. 3 is a vertical section taken on the line 65 3-3 of Fig. 2,

Fig. 4 is a detail perspective of the blade holder viewed from the top in Fig. 1,

Fig. 5 is a top plan view of the face side of a modified form of blade holder.

Fig. 6 is a plan view of the rear or back face 70 of said holder,

Fig. 7 is a vertical section on line 7-7 of Fig. 6,

Fig. 8 is a detail of the blade retaining clip used in both forms of the blade holder. 75

Referring to the drawings:—In the form of the invention shown in Figs. 1—4 and 8, the blade holder comprises opposed plates connected at their upper ends and which may be formed by the usual expedient of bending a 80 strip of metal upon itself. The uppermost plate 1 of the two constitutes the razor blade backing plate and the lower or underplate 2 connected therewith at the top is preferably formed centrally with a pocket 3 therein by 85 upsetting the material in a suitable press, this providing at this point, an offset in the rear plate. This offset portion is reversely upset to provide a handle socket 4 and inwardly extending boss 5 in continuation. This 90

boss terminates a short distance from the rear or bottom face of the blade backing plate 1 and the upper or junction edge of the plates 1 and 2 are formed with an elongated slot 6 therein. Adjacent to the bottom edge of the blade backing plate 1, an upstanding blade positioning bar 7 is appropriately connected to its edges, as by welding, and is spaced from its face to overlie an inserted razor blade 8 of the single edged variety, the rear or non-cutting edge of which is provided with the usual metal clip 9. The upper edge of the positioning bar 7 engages the lower edge of the clip 9 and determinately positions the lower cutting edge of the blade. The blade is held in cooperative relation to the positioning bar 7 and against movement from the blade holder by means of a blade clamping member, approximating in cross section an inverted U in shape, with an outer arm 11 overlying the 105 110

clipped edge of the blade and with its inner arm 12 extended through the elongated slot 6 to a position alined with the boss 5 of the handle receiving bore 4 where it is clamped by 5 the end of the handle 10. The upper edge of the blade clamp is formed with an upraised tab or finger piece 13 which may be suitably formed as, for example, by slitting and bending upwardly the metal of the clamp as suggested in Fig. 8.

Depending from the handle holding plate, and positioned below the cutting edge of a supported blade is the guard bar 14, which in the form shown in Figs. 1-4 presents an unbroken rectilinear skin contacting edge 15 in advance of the cutting edge of the blade and an adjacent lather collecting body portion 16. The bar 14 is of substantial width relatively to its thickness to provide for the accumulation of a reasonable amount of lather ahead of the blade which as will be seen, is supported by the holder with its entire cutting edge unobstructed. The guard edge 14 is forward from this cutting edge so that the full width 25 of the blade is available for shaving. The operation is facilitated and the tautening of the flesh in advance of the blade edge is effected by the unobstructed edge of the supported blade and the rectilinear edge of the guard 30 in cooperation. The action simulates closely that which occurs when shaving is effected by the so-called "old fashioned" method of "straight blade" razor and hand tautened skin. The guard bar 14 is connected to the 35 plate 3 by any appropriate means. As shown, one such means may be in the form of depending arms 17 connecting the edge of the plate 3 and the contact edge of the bar. It will be obvious that the bar and connecting arm 17 40 may constitute an integral part of the plate 3 and may be stamped out therefrom. The arms 17 are preferably corrugated as shown for strength. In the form of the invention shown in Figs. 5-7, the construction is, in essence, modified as regards the form of depending guard member only. Similar numbers as those employed in Figs. 1 to 4 therefore designate corresponding parts of the structure. The modified form of guard 45 member is provided by a series of approximately semi-circular teeth 18 (Fig. 7) which may be an integral part of the rear plate 3 or handle receiving member of the holder and similarly to the bar guard 14 first described, 50 may be die'd out from the sheet metal of the holder or otherwise appropriately formed. The approximately circular metal of the guard, the edges of which form a broken rectilinear contact edge positioned in advance of 55 the cutting edge of the razor blade, provides a lather pocket into which a substantial portion of the lather in advance of the blade will be drawn during the shaving operation. The curved body of the blades therefore provides 60 a lather collecting body portion for the guard 65

similarly to the face 16 of the guard bar 14 of the first form described.

The advantages achieved by the described constructions have been previously discussed in full and need not be repeated. The disclosed specific forms of invention represent preferable embodiments, but are susceptible of variation within the spirit of the invention and the scope of the claims.

Having described the invention, what I claim and desire to secure by Letters Patent is:

1. In a safety razor for blades having clips attached to their rear edges, a blade holder having its forward edge provided with a raised cross bar arranged to engage the front edge of the clip of a razor blade and to position said blade with its full cutting edge entirely free and unattached, and a guard connected with the holder and having its guard edge positioned in advance of the cutting edge of the blade and out of contact therewith.

2. In a safety razor for blades having clips attached to their rear edges, a blade holder having a blade backing member with a cross bar at its front edge upstanding from its face to overlie a razor blade and to engage the front edge of its clip and position the cutting edge of the blade forwardly of said backing member and entirely free and unattached, and a guard depending from said holder having its guard edge positioned in advance of the cutting edge of the blade, said guard member rearwardly of its guard edge, being formed to provide an adjacent lather collecting pocket.

3. In a safety razor, a blade holder comprising a blade backing plate, a spaced and connected handle receiving plate bored to receive the threaded end of a handle, a stop bar upstanding from the backing plate to overlie a razor blade and engage the edge of its clip thereby to position its cutting edge with relation to the holder, a blade clamp overlying the rear clipped edge of the blade and having a portion engaged and held in blade clamping position by the threaded end of the holder handle, and a guard depending from said holder with its edge positioned in parallel to and in advance of the blade cutting edge.

4. In a safety razor, a blade backing plate of bifurcated formation providing a front blade backing face and a rear handle attaching plate having a threaded handle receiving bore therein with a slotted opening between said faces, and a U-shaped blade clamping plate having one arm of the U extending through the slotted opening to aline with said socket and contact the handle end, and the other arm to overlie and clamp an edge of the razor blade.

5. In a safety razor, a blade backing member having an upper plate upon which the blade seats provided with a stop thereon determinately to position the cutting edge of

the blade in advance of said plate, said back-
ing member having a lower base plate ex-
tended to form a guard member and provided
with a pocket and a threaded handle bore en-
tering said pocket, a handle having an end
threaded to screw into said bore, a detachable
clamp of approximate U-shape having one

arm arranged to slide over and overlie and
clamp the inoperative edge of the blade down
on said upper plate and having its other arm ¹⁰
arranged to extend into said pocket and over-
lie said bore for engagement by the threaded
end of the handle.

EDWIN L. CONNOR.
